PLASTIC AND VISCOUS MATERIAL MIXING DEVICE

Allen L. Stone, Los Angeles, Calif., assignor to
Pneumastic Co. Inc., Los Angeles, Calif., a corporation of Nevada

Application March 23, 1940, Serial No. 325,579

15 Claims. (Cl. 259—145)

This invention relates to a device for mixing viscous and plastic materials in which the various ingredients, such as the binding agent and the aggregate, are conveyed in measured amounts to a mixing passage where the mixing operation is performed. More particularly it relates to a device of the character referred to which is especially useful for mixing aggregate and viscous binding material such as emulsified asphalt, petroleum base asphalt or coal tar products, and for applying the mixture to a desired surface which is to be coated. A mixing device of this general character is disclosed in my copending application Serial No. 203,077, filed April 20, 1938, for Plastic material mixing device, now Patent No. 2,213,640.

It is a general object of the invention to provide an improved device for mixing viscous or plastic materials with an aggregate for application to a surface to be coated.

Another object of the invention is to provide mixing apparatus of the character referred to which can handle a wide range of sizes of aggregate in performing the mixing operation.

Another object of the invention is to provide an improved mixing passage construction wherein a more efficient mixing operation is performed than in similar passages heretofore provided.

Another object of the invention is to provide an improved method of constructing a resilient mixing device to enhance the operating characteristic thereof as well as to provide for economical manufacture.

Other objects and advantages of the invention will be apparent from the following description of a preferred embodiment thereof as illustrated in the accompanying drawing, in which:

Figure 1 is a longitudinal sectional view through a mixing device embodying my invention;

Figure 2 is a plan view partly in section of the device shown in Figure 1; the plane of section being indicated by the line 2—2 of Figure 1.

Figure 3 is a sectional view taken in a plane indicated by the line 3—3 in Figure 1.

Figure 4 is a sectional view taken in a plane indicated by the line 4—4 in Figure 1.

Figure 5 is an enlarged detail view of a portion of the wall of the mixing passages in the resilient body.

Generally the mixing device of my invention comprises a resilient body, preferably of elongated form and having a longitudinal mixing passage formed therein, which is of a tortuous or zigzag character and has alternate enlargements

and restrictions so that the material laden air stream will be alternately expanded and compressed while changing its direction of movement as it flows through the passage, so as to repeatedly strike and rebound from the resilient walls defining the passage. Measured amounts of both the aggregate and the binding materials such as emulsified asphalt are supplied to a feed chamber under considerable pressure and as they pass through the mixing passage a pulsating action is set up which tends to further facilitate the rebound and mixing action of the materials as they travel through the passage.

Referring to Figures 1 and 2 the mixer may comprise an elongated casing 10 which may have a plurality of apertures 11 for a purpose later described. Within the casing 10 an elongated resilient body 12 may be provided which is preferably molded of rubber as described in detail hereinafter. Body 12 has a feed chamber 13 at one end and a discharge tube or throat 14 at the other end extending beyond a shoulder 16 of the body 12. The discharge tube 14 may be positioned within the casing 10 by means of ringlike collar 17 of resilient material which is secured as by bolts 18 against an inturned flange 19 of the casing 10. Collar 17 also provides for lateral flexing movement to accommodate a certain amount of limited endwise movement of discharge tube 14.

At its feed end the body 12 has its end disposed within a cup-shaped end plate or collar 20 slidably disposed within the end of the casing 10 and adapted for movement relative thereto to permit limited elongation and contraction of the resilient body 12. Spring 21 seats against the end of collar 20 and an adjustable collar 22 slidably engaged about casing 10. To limit the positioning of collar 22 under the influence of spring 21, adjusting bolts 23 may be provided which extend through bosses 24 on collar 22 and have their heads engaged with apertured ears 25 on casing 10. If desired, a recoil spring 23a may be placed around bolts 23 between each boss 24 and the aligned ear 25.

To provide for feeding of material to the chamber 13, the resilient body 12 may have molded or otherwise suitably secured therein a threaded feed tube 26 which is secured to collar 20 by suitable lock nuts and which discharges substantially lengthwise of the casing. For example, tube 26 may be used to feed aggregate carried by an air stream through a suitable feed hose (not shown). To provide for introduction of a binding material such as emulsified asphalt,

a second feed tube 27 is provided which leads to a self-closing nipple-type nozzle 27a, having its end walls slotted in two planes at right angles to form the segments of the nipple. The nozzle 27a opens generally downwardly toward the bottom wall of the chamber 13 to intersect the path of discharge from aggregate feed tube 26.

As seen in Figure 1, the body 12 is provided with a tortuous mixing passage which in the embodiment illustrated has a substantially constant dimension in the plane of Fig. 1. In a direction at right angles to the plane of Fig. 1, as seen in Fig. 2, the walls of the passage alternately approach and recede to form successive remixing chambers 28 which are separated by restricted passages or restrictions 29. Similarly the outer walls of the body 12 have the same tortuous shape and alternately contact and recede from the casing 10. Thus, the body 12 is free to move with reference to the casing both as to elongation and as to lateral expansion. As is pointed out later, in operation an actual pulsation of the body 12 is set up to facilitate the mixing action by constant motion of the walls surrounding the elongated passage.

In order to facilitate the dispersing and mixing operation dispersing or deflecting means may be provided in the passage in the form of integrally molded buttons 31 which are of rounded contour and are disposed in opposed relation in the feed chamber 13 and in the respective mixing chamber 28 as seen most clearly in Fig. 1.

To insure sealing of the rubber body 12 and to provide a controlled expansion thereof, the body 12 is formed of an inner portion 32 which is molded and an outer covering 33 which is vulcanized thereon. After molding the core may be removed from body 12 by sealing one end thereof and then expanding the body to facilitate withdrawal of the core. The expansion may be accomplished by forcing grease or some other suitable material into the mixing passage under pressure.

In order to facilitate and control the pulsating action of the body at various points along its length, the outer covering is formed with a varying thickness along the mixing passage, with the thickness reducing generally from the feed and to the discharge end of said passage. Preferably the covering at 33a about the feed chamber 13 is of substantial thickness as compared to other portions of said covering indicated at 33b and 33c.

In practice the re-enforcing may be effected and controlled by winding pure gum rubber strips about the body 12 to provide a different number of layers at desired locations therealong. Usually the entire body will be covered with a single layer of sealing rubber, while additional re-enforcing is provided as may be desired. As shown, the heaviest re-enforcing is provided along the feed chamber 13 and the first mixing chamber 28, the second mixing chamber 28 is provided with a medium amount of re-enforcing, indicated at 33c, and the final mixing chamber 28 is provided with a lighter re-enforcing as indicated at 33b. After the gum rubber strips are wound about the body, the assembly is placed in a suitable fixture and a vulcanizing operation is performed to provide an integral bond between the rubber re-enforcing strips and the molded portion 32 of the body 12.

In actual practice, resilient bodies have been made wherein a wall thickness and re-enforcing is provided which will resist an expansion pres-

sure up to substantially 80 lbs./sq. inch at the feed chamber, 40 lbs./sq. in. in the second chamber 28, and 20 lbs./sq. in. in the final mixing chamber 28, and the discharge tube. If desired, the re-enforcing of the restrictions 29 may be controlled to resist expansion under pressure up to 60 lbs./sq. in. at the first and 30 lbs./sq. in. at the second.

Means may be provided for enabling adjustable restrictions in the passage means, and for this purpose leaf springs 36 (Fig. 1) may be provided having curved ends 37 engaging body 12 at the flat side of a pair of adjacent mixing chambers 28. Each spring 36 may be carried by a screw 39 engaging a threaded fitting 41 mounted in the wall of casing 10. A suitable lock-nut may be associated with each spring. As shown, two sets of passage restricting means may be provided. The ends of springs 36 are engaged with the wall portions having buttons 31 and adjustment of springs 36 may be made to engage the opposed buttons 31 in the second mixing chamber 28 as indicated in dotted lines in Figure 3. With such restriction to form a divided mixing chamber, the combined cross-sectional areas of the divisions thereof are still greater than the cross-sectional area of a restriction 29.

In operation, for example, for mixing a viscous material such as emulsified asphalt with an aggregate, a metered amount of the emulsified asphalt may be supplied through the fitting 26 under a pressure of say 90 lbs. per square inch while the aggregate may be introduced through the fitting 27 in an air stream having a pressure of say 60 lbs./sq. inch. The aggregate may range in size from 200 mesh screenings up to pieces having a diameter of $\frac{1}{2}$ " to $\frac{3}{4}$ ".

The stream of binder, such as emulsified asphalt, from the nozzle 27a will enter the feed chamber 13 and cross the stream of air and aggregate from the feed fitting 26, so that the mixed streams will impinge against the lower wall of the feed chamber to rebound with a swirling action within such feed chamber. This first phase of the mixing action which occurs in the feed chamber and the first mixing chamber 28, which opens into such feed chamber without restriction, may be said to be an expanding phase wherein the two streams of material are ejected from confined passages under pressure into the larger feed chamber to expand as they enter such feed chamber. The reinforcing of the feed chamber 13 would be selected so as to prevent expansion thereof under a selected pressure, say 80 pounds per square inch.

The material in passing from the feed chamber 13 into the first mixing chamber 28 must change its direction and at the same time it encounters the two dispersing buttons 31 in such chamber to be further broken up and intermingled thereby. It will be noted that as the material leaves the feed chamber 13 and passes into the first mixing chamber 28, the cross-sectional area of the mixing passage will gradually decrease until the first restriction or throat 29 is encountered.

Because of the restriction provided at the throat 29, the pressure will be built up at this throat until it is relieved by the expansion thereof permitted by the free space 42 around the first throat 29. The pulsating action caused by successive building up and relief of pressure at the first throat 29 occurs rapidly so that the walls of the throat pulsate or vibrate in a very rapid manner. Thus, the second phase of the mixing action is a restriction of the material in space of

smaller cross-sectional area, while at the same time the direction of flow of the material is again changed as the material leaves the first restriction or throat 29. As the material leaves the throat it virtually explodes as it rapidly expands in entering the second mixing chamber 28.

It will be noted that no jamming can occur at the restriction 29 because of the free expansion provided thereby, so that larger pieces of aggregate will be freed and carried on through the mixing chamber. Again in the second mixing chamber 28 the material encounters a pair of dispersing buttons 31 to enhance the dispersion and to promote intimate intermingling of the materials.

The second chamber 28 is provided with a reinforcing thereabout to prevent expansion, say up to 40 lbs. of pressure, and from this mixing chamber the material must proceed through the second restriction 29 having a lesser amount of re-enforcing, say for 30 lbs./sq. in. pressure. A pulsation will also be set up at this point causing rapid rebounding and intermingling of the material passing therethrough. From the second restriction 29, material in substantially mixed condition expands into the last mixing chamber 28, where again a pair of dispersing buttons 31 perform a further dispersing action and the final mixing is effected with each particle of aggregate thoroughly coated with the binder. The mixed material is discharged under considerable pressure through discharge outlet 14 in the form of a substantially continuous, homogeneous stream or spray for impact application to the surface to be coated. The discharge tube 14 can expand into the space thereabout to prevent jamming of pieces of aggregate such as small rock in this location.

In the event of heavy feeding of material under high pressure the entire body 12 can elongate against the pressure of spring 21, and the amount of such elongation can be controlled by adjusting spring 21. The length of the passage is determined by the character of the material to be mixed and the use for which it is intended, as well as the desired constituency of the discharged product. For thinner mixes a shorter passage may be employed as well as where considerable pressure is desired for application. For materials requiring a longer mixing action or for heavier materials a longer passage may be used. Adjustment of spring 21 to lengthen or shorten the space occupied by the resilient body also decreases or increases the angularity of the direction change of the material in passing from chamber to chamber.

It is to be noted that adjustment of springs 41 also serves to change the character of the mixing chambers by varying the spacing between the opposed dispersing buttons 31. For example, as shown in dotted lines in Figure 3 the buttons 31 may be adjusted to engage each other and thereby divide the mixing chamber. Generally, for mixing with light viscous liquids with a high setting power, a minimum or no spring pressure is employed and the passage is left open to its greatest extent and a high aggregate pressure is employed. With heavier viscosities and slower setting up characteristics, a lower aggregate pressure is used and the flow restricted by increasing the pressure of springs 36.

The pulsating action referred to is controlled both by controlling the passage restriction by use of springs 36, by varying the elongation characteristics by changing the compression of spring 75

21, and by varying the pressures on the binder and aggregate materials. In general, adjustment should be made to build up pressures and restrict the flow where vigorous pulsating action is desired.

I claim:

1. A plastic and viscous material mixing device comprising a casing, a resilient body mounted in said casing having a tortuous passage extending therethrough, said tortuous passage having alternate enlargements and restrictions therein, and the discharge end of said passage comprising a resilient discharge tube projecting from said casing, said body having portions engaging said wall and other portions spaced therefrom to enable expansion and contraction of the body, and a resilient collar positioning said tube with respect to said casing.

2. A plastic and viscous material mixing device comprising a casing, a resilient body mounted in said casing having a tortuous passage extending therethrough, said tortuous passage having alternate enlargements and restrictions therein, the discharge end of said passage comprising a resilient expandable tube projecting from said casing, said body having portions engaging said wall and other portions spaced therefrom to enable expansion and contraction of the body, a resilient collar positioning said tube with respect to said casing, and yieldable means interposed between an end of said body and the adjacent end of said casing providing for elongation of said body within said casing.

3. A plastic and viscous material mixing device comprising a casing, a resilient body mounted in said casing having a tortuous passage extending therethrough, said tortuous passage having alternate enlargements and restrictions therein, said body having portions engaging said wall and other portions spaced therefrom to enable expansion and contraction of the body, and yieldable means interposed between an end of said body and the adjacent end of said casing providing for elongation of said body within said casing.

4. A plastic and viscous material mixing device comprising an elongated casing, an elongated resilient body mounted in said casing having a tortuous mixing passage extending therethrough, said body being free for elongation and contraction during a mixing operation, and adjustable means for compressing said body lengthwise in said casing.

5. A plastic and viscous material mixing device comprising an elongated casing, an elongated resilient body mounted in said casing having a tortuous mixing passage extending therethrough, said body being free for elongation and contraction during a mixing operation, and adjustable means for yieldably resisting elongating movement of said body.

6. A plastic and viscous material mixing device comprising a casing, a resilient body mounted in said casing having a tortuous passage extending therethrough, said tortuous passage having a plurality of mixing chambers separated by restrictions, and material dispersing means in opposed relation upon opposite walls of said mixing chambers, said dispersing means comprising opposed rounded buttons projecting inwardly from opposed walls of each of said chambers.

7. A plastic and viscous material mixing device comprising a casing, a resilient body mounted in said casing having a tortuous mixing passage extending therethrough, said tortuous pas-

sage having alternate enlargements and restrictions therein, and resilient re-enforcing means about the said body providing for different expansion pressures for said restrictions and said enlargements.

8. A plastic and viscous material mixing device comprising a casing, a resilient body mounted in said casing having a tortuous mixing passage extending therethrough, said tortuous passage having alternate enlargements and restrictions therein, said body being constructed to provide for different expansion pressures along said body with said pressures decreasing from the feed end of said passage to the discharge end thereof.

9. A plastic and viscous material mixing device comprising a casing, a resilient body mounted in said casing having a tortuous mixing passage extending therethrough, said body also being spaced from said casing at various points to provide for expansion and constriction of said body, and said body being formed to provide different expansion pressures along said passage.

10. A plastic and viscous material mixing device comprising a casing, a resilient body mounted in said casing having a tortuous mixing passage extending therethrough, said passage having a series of mixing chambers separated by restrictions, said body also being spaced from said casing at various points to provide for expansion and contraction of said body, and said body being formed to provide different expansion pressures along said passage and with the smaller expansion pressures at said restrictions.

11. A plastic and viscous material mixing device comprising a casing, a resilient body mounted in said casing having a tortuous mixing passage extending therethrough, said passage having a series of chambers separated by restrictions, said body also being spaced from said casing at various points to provide for expansion and contraction of said body, and said body being formed to provide different expansion pressures along said passage with the expansion pressures of the chamber walls decreasing successively from the feed to the discharge end of said passage, the expansion pressures of said restrictions being the order of the pressure at the discharge end of said passage.

12. A plastic and viscous material mixing device comprising a casing, a resilient body mount-

ed in said casing having a tortuous passage extending therethrough, said tortuous passage having alternate enlargements and restrictions therein, and said body alternately engaging and receding from said casing, the discharge end of said passage comprising a normally open throat which is capable of expansion to pass an obstruction, and yieldable means for positioning said throat with respect to said casing, said means being yieldable axially of said casing to permit contraction and expansion of said body and being yieldable radially of said casing to allow expansion for an obstruction.

13. A plastic and viscous material mixing device comprising a casing, a resilient body mounted in said casing having a tortuous passage extending therethrough, said tortuous passage having alternate enlargements and restrictions therein, and said body alternately engaging and receding from said casing, the discharge end of said passage comprising a normally open throat capable of expansion to pass an obstruction, yieldable means supporting said throat with respect to said casing, and resilient means for controlling longitudinal expansion and contraction of said body within said casing.

14. A resilient mixing member having a tortuous passage extending therethrough, said passage having successive enlargements and restrictions therein, which comprises a molded body portion of resilient material such as rubber, and a covering of a rubber material disposed about said body portion, said covering having alternating portions of varying thicknesses along said body portion to obtain desired wall strengths of varying amounts with the thicker portions encompassing the passage enlargements, the covering material being bonded to the body portion.

15. A resilient mixing member having a tortuous passage extending therethrough, which comprises a molded body portion of a resilient material such as rubber, and a covering of sheet rubber material disposed about said body portion to provide alternating portions of varying wall thicknesses along the passage with the thickness of the thicker portions decreasing from the feed end toward the discharge end of said member, the covering material being bonded to the body portion.

ALLEN L. STONE.
